Geo. P. Kimmel

ATTORNEY.

FIG. 5.

UNITED STATES PATENT OFFICE

ANTHONY SKINDEL, OF WILDWOOD VILLAS, NEW JERSEY

AIR RIFLE

Application filed February 18, 1931. Serial No. 516,771.

This invention relates to an air rifle and has for its object to provide, in a manner as hereinafter set forth, a rifle of such class whereby the projectile to be discharged therefrom is projected by compressed air supplied from a source remote from and permanently communicating with the rifle.

A further object of the invention is to provide, in a manner as hereinafter set forth, 10 an air rifle including a compressed air receiving chamber normally closed to a pressure relieving chamber and in communication with a compressed air source remote from the rifle, and a trigger operated means 15 for establishing communication between the chambers to provide for the discharge of the projectile by compressed air.

Further objects of the invention are to provide, in a manner as hereinafter set forth, an 20 air rifle which is simple in its construction and arrangement, strong, durable, compact, thoroughly efficient when used, conveniently discharged and comparatively inexpensive to manufacture.

25 With the foregoing and other objects in view, the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope 30 of the claims hereunto appended.

35 In the drawings wherein like reference characters denote corresponding parts throughout the several views:—

Figure 1 is a side elevation of an air rifle and its compressed air supply attachment in 40 accordance with this invention.

Figure 2 is a fragmentary view in longitudinal section.

Figure 3 is a disassembled view of the combined closure and coupling disc for the air chamber and compressed air conducting line and illustrating the latter as detached from the closure.

Figure 4 is a fragmentary view in longitudinal section of a modified form of air rifle.

50 Figure 5 is a fragmentary view partly in

longitudinal section and upon a reduced scale of another modified form of air rifle.

Referring to Figures 1, 2, 3 and 4 of the drawings, 1 indicates the stock and 2 the body portion of the rifle. The rear end of the body 55 portion 2 is fixedly secured to the forward end of the stock 1, and the latter is disposed at a downward inclination with respect to body portion 2.

The body portion 2 includes a barrel part 60 3 of less length than body portion 2 and the bore of part 3 is indicated at 4.

The body portion 2 intermediate its ends and in its upper part is formed with a pressure release chamber 5 which permanently 65 communicates with the inner end of the bore 4. The bottom 6 of chamber 5 has a compressed air intake 7. That part of the wall of chamber 5 which opposes the inner end of the bore 4 is formed with an opening 8. 70

The body portion 2 rearwardly of the chamber 5 is formed with a pull bar chamber 9 having its rear end closed by the forward end of stock 1. The body portion 2 is formed below part 3, chamber 5 and chamber 9 with 75 an opening which extends from the rear end to the forward end of body portion 2. The rear end of such opening is closed by the forward end of stock 1. Arranged within such opening rearwardly of the chamber 5 and below the chamber 9 is a partition 10 which in connection with a closure disc 11 for the forward end of such opening provides a compressed air receiving chamber 12. The wall 80 of the lengthwise extending opening in body portion 2 and at the forward end thereof is threaded as at 12. The closure or disc 11 has its edge threaded for engagement with the threads 12 whereby the element 11 is detachably secured in position. The element 11 provides what may be termed a combined closure 85 for the air chamber 12 and a coupling means for a compressed air conducting pipe 13 which leads from a compressed air storage tank 14. The element 11 is formed with an axial opening 15 having a threaded wall with 90 which engages the threaded upper end of an angle-shaped member 16 forming a part of the line 13 and the major portion of such line is flexible.

The bottom wall of the chamber 9 is slotted as at 17. The bottom wall of the lengthwise extending opening rearwardly of the partition 10 is slotted as at 18. The slot 17 is arranged over slot 18 and extending through said slots and into chamber 9 is a trigger 19 which is pivoted to the body portion 2 as at 20. The pivot is arranged below the upper end of trigger 19. Pivoted to the upper end 10 of trigger 19, as at 21 is a forwardly extending pull bar 22 which projects through the opening 8 and into the chamber 5. The forward end of pull bar 22 has pivotally connected therewith a depending link 23 which 15 extends through the opening 7 and is pivotally connected at its lower end to a controlling valve 24 for the opening 7. The valve 24 is arranged below the bottom 6 of chamber 5 and includes a stem 25 which passes through a guide member 26 arranged in the compressed air receiving chamber 12.

The projectile is indicated at 27 and which is mounted against a seat 28 formed at the inner end of the bore 4.

The form shown in Figure 4 is constructed in the same manner as that shown in Figure 2, with this exception that the element 11 is removed and a valve-controlled partition member 29 is arranged within the lengthwise extending opening in body portion 2 and contacts with the partition 10 to provide a compressed air receiving chamber 30 of materially less length than the chamber 12. The compressed air for the chamber 30 is supplied by a compressed air conducting line 31 which leads from the tank 14 and is connected to the bottom of body portion 2 and opens into chamber 30 rearwardly of partition 29. The valve controlled partition 29 can also be employed when the element 11 couples the line 13 of body part 2 and when so employed the conducting line 31 is disconnected from body part 2 and the opening to receive said conducting line 31 is plugged. The port for the passage of air through the valve controlled partition 29 is indicated at 32 and such port is closed when the conducting line 31 is employed but when element 11 couples line 13 in position, the air pressure will shift the valve part of the partition 29 to open port 22.

In the form shown in Figure 5 the body part is indicated at 33 and includes an extension 34 providing a continuation of the barrel portion 34'. The lower portion 35 of body part 33 provides the compressed air receiving chamber 36 having an integral forward end. The line 37 for conducting compressed air from tank 14 opens into the bottom of chamber 36.

Otherwise than that as stated the forms shown in Figures 4 and 5 will be the same as the form shown in Figure 2.

If desired the trigger 19 may be provided with a controlling spring to assist in restor-

ing it to normal position, but the pressure of air acting on valve 24 when the trigger is released will cause the latter to be moved to normal position.

When the lower portion of the trigger is moved rearwardly the push or pull bar 22 will be carried forwardly due to the upper end of the trigger swinging forwardly on its pivot. The forward movement of the push, pull or operating bar will cause the link 23 to lower carrying the valve 24 therewith and opening the chamber 5 to chamber 12. The passage of the compressed air to chamber 5 will cause the projectile 27 to be discharged from the rifle, as chamber 5 is closed other than the point of communication with the inner end of bore 4. When the trigger is released the pressure of air in chamber 12 will act on valve 24 and shift it to close the bottom of chamber 5.

What I claim is:—

1. An air rifle comprising a body portion having a barrel port provided with a bore, a pressure relieving chamber at the rear of said port and permanently opening into the bore, a compressed air receiving chamber below said other chamber and bore, a pull bar chamber at the rear of the pressure relieving chamber, a compressed air supply line opening into said receiving chamber, a normally closed valve for controlling communication between said chambers, and shiftable means carried by said body portion and extending through the pull bar chamber and into the pressure relieving chamber for shifting said valve to establish communication between said pressure relieving and air receiving chambers to provide for the discharge of a projectile mounted in said bore, said means including a pull bar.

2. An air rifle comprising a body portion having a barrel port provided with a bore, a pressure relieving chamber at the rear of said port and permanently opening into the bore, a compressed air receiving chamber below said other chamber and bore, a compressed air supply line opening into said receiving chamber, a normally closed valve for controlling communication between said chambers, a link depending into said pressure relieving chamber and connected to said valve, a pull bar connected to said link arranged rearwardly of the latter, and a pivoted trigger connected to said bar for shifting it forwardly to move said valve to open position for establishing communication between said chambers to provide for the discharge of a projectile mounted in said bore, and a guide within the air receiving chamber for said valve.

3. In an air rifle, a body portion formed with a chamber disposed longitudinally thereof, a pressure relieving chamber at its forward end of said other chamber and having an apertured bottom, a barrel part hav-

ing its bore opening at the rear into said pressure relieving chamber, a compressed air receiving chamber arranged below said relieving chamber and bore and opening into 5 said pressure relieving chamber, and superposed spaced slots rearwardly of said relieving and receiving chambers, a valve normally closing the receiving chamber to the relieving chamber, an inclined shifting means for 10 said valve arranged in the relieving chamber, a pull bar operating in said longitudinal chamber, extending into said relieving chamber and connected to said means, a pivoted lever extending through said slots and connected to the rear end of said bar for operating 15 it to open said valve, and means for supplying compressed air to the receiving chamber.

In testimony whereof, I affix my signature
20 hereto.

ANTHONY SKINDEL.
